UNDERCOVER SMALL ARMS SHOULDER HOLSTER

Arthur M. Kassel, 2647 Hubbard St.,
Brooklyn, N.Y. 11235

Filed Aug. 3, 1967, Ser. No. 8,113

Term of patent 14 years

Int. Cl. D22—04

U.S. Cl. D22—13

FIG. 2 is a side elevational view thereof.

The broken line illustration in FIG. 1 showing how the shoulder holster is worn and used is depicted for illustrative purposes only.

I claim:

The ornamental design for an undercover small arms shoulder holster, substantially as shown and described.
